CLOTHESLINE STRETCHER

Violetta H. Hill and Roland R. Hill, Clifton, N. J.

Application March 1, 1949, Serial No. 78,914

2 Claims. (Cl. 211—119.15)

1

This invention relates to a clothesline stretcher. The object of the invention is to provide a device for releasably connecting the ends of a flexible clothesline together.

Another object of the invention is to provide a manually-operable device for stretching a clothesline to give it the desired tension.

A further object of the invention is to provide a clothesline stretcher which is extremely simple and inexpensive to manufacture.

Other objects and advantages will be apparent during the course of the following description.

In the accompanying drawings forming a part of this application, and in which like numerals are employed to designate like parts throughout the same:

Figure 1 is a side elevational view showing the stretcher in initial position and applied to a clothesline to be stretched;

Figure 2 is a top plan view of the stretcher in the position of Figure 1;

Figure 3 is a central longitudinal sectional view of the stretcher in initial position and applied to a clothesline to be stretched;

Figure 4 is a central longitudinal sectional view of the stretcher showing the position of the parts after the stretching lever has been moved to its full extent;

Figure 5 is a sectional view taken on the line 5—5 of Figure 1;

Figure 6 is a side elevational view of the support member of the stretcher;

Figure 7 is a side elevational view of the stretching lever;

Figure 8 is a plan view of the support member;

Figure 9 is a plan view of the stretching lever.

Referring in detail to the drawings, the numerals 10 and 11 designate a pair of pulleys which are rotatably supported on a suitable support by braces 12 which are provided with a hook 13 on an end thereof. Trained over the pulleys 10 and 11 is a clothesline 14 and the present invention is directed to a stretching device for securing the clothesline 14 on the pulleys and maintaining the clothesline 14 stretched under tension.

The stretcher is fabricated of suitable material and comprises a support member 15 which is bent to provide a bottom wall 16 and a pair of spaced, parallel side walls 17 and 18. Secured to one end of the support member 15 is a ring 9 to which is attached an end of the clothesline 14. Projecting from the other end of the support member 15 is a pair of spaced, parallel ears 19

2

and extending between the ears 19 is a pin or roller 20 for a purpose to be later described. Arranged adjacent the ring 9 and positioned between the side walls 17 and 18 is a locking dog 21 having clothesline-engaging teeth 22 on its inner end, and the dog 21 is pivotally connected to the support member 15 by means of a pin 23.

The stretcher further includes a lever 24. Extending from one end of the lever 24 is a tubular handle 25 which is adapted to be gripped by the user to pivot the line. Formed integrally with the free end of the handle 25 is a hook 26 for engagement with a portion of the clothesline when the line is stretched. The lever 24 is curved or channel shaped in cross section to define a longitudinally-extending socket for receiving the support member 15 when the clothesline is not being stretched.

A body member 27 is interconnected to the lever 24 by means of a tapered portion 28 and the body member 27 comprises a pair of spaced, parallel side portions 29 and 30 which are positioned between the ears 19. The pin 20 pivotally connects the side portions 29 and 30 to the ears 19. Extending between the side portions 29 and 30 is a pin 31 provided with a roller 32 for a purpose to be later described.

In use, the rope clothesline 14 is trained over the pulleys 10 and 11 and one end of the line is connected to the ring 9. The other end of the rope line 14 is threaded through the stretcher as follows: First, the line is passed over pin 32, then under pin 20 and the line 14 is threaded under locking dog 21, Figures 1, 2 and 3. After the line 14 is threaded in this manner, the line is stretched as tight as possible by hand and locked by the dog 21. The lever 24 is then pivoted through an arc of 180° to the position shown in Figure 4, and the hook 26 is moved into engagement with the line 14. This movement of the lever will further stretch the line so that it will be under a tension not previously obtainable. When the clothesline 14 is not being used, the lever 24 is pivoted back to the position shown in Figures 1, 2 and 3, so that the line 14 will not be under continued unnecessary stress.

As many embodiments may be made of this inventive concept, and as many modifications may be made in the embodiment hereinbefore shown and described, it is to be understood that all matter herein is to be interpreted merely as illustrative and not in a limiting sense.

We claim:

1. In a clothesline stretcher, a support member,

a ring projecting from one end of said support member for engagement with one end of said clothesline, a locking dog arranged adjacent said ring and pivotally connected to said support member, a pair of spaced, parallel ears extending from the other end of said support member, a lever arranged contiguous to said support member, said lever embodying an actuating handle projecting from one end thereof, a hook arranged on the projecting end of said handle and secured thereto, a body member on the other end of said lever and positioned between said ears and pivotally connected thereto, and a pin carried by said body member for engagement with a portion of said clothesline.

2. In a clothesline stretcher, a support member, a ring projecting from one end of said support member for engagement with one end of said clothesline, a locking dog arranged adjacent said ring and pivotally connected to said support member, a pair of ears extending from the other end of said support member, a lever arranged contiguous to said support member, said lever embodying an actuating handle pro-

10

20

jecting from one end thereof, a hook arranged on the projecting end of said handle and secured thereto, a body member on the other end of said lever and positioned between said ears and pivotally connected thereto, and means carried by said body member for engagement with a portion of said clothesline.
